AUTOMATIC LOWERING DEVICE

Edgar Schoene, Orchard Farm, Mo.

Application May 8, 1936, Serial No. 78,548

5 Claims. (Cl. 254—160)

This invention relates to certain new and useful improvements in automatic lowering devices, and more specifically to its use in lowering persons of various weights escaping from a burning 5 building—the peculiarities of which will be hereinafter fully described and claimed.

Rope ladders, block and tackle or the like, require cooperative action by the person using them to regulate the speed of descent and to counter- 10 act too speedy movement.

My device can be adjusted to different weights for gravitating descent, so as practically to regulate the speed of descent as desired, and produce automatically a substantially uniform rate with- 15 out attention of the person being lowered, or of the attendant; for instance, my device can be attached by a rescuer to a person overcome by smoke or otherwise incapacitated from aiding himself, gently pushed over the window sill and left by his rescuer to descend at a reasonably 20 safe rate of speed to the ground, while another unconscious person or a child, is being brought to the window for lowering in turn. Valuable time is saved thereby.

25 In the accompanying drawing in which like reference numerals indicate corresponding parts, Fig. 1 represents a front view partly in section, of my device mounted above a window;

Fig. 2, a vertical sectional view through the 30 casing on the line 2—2 of Fig. 1, showing a side view of the machine mounted therein;

Fig. 3, an enlarged sectional elevation on the line 3—3 of Fig. 2, showing a front elevation of the machine and partial section; and

35 Fig. 4, a vertical section on the line 4—4 of Fig. 3, showing the regulating valve.

Referring to the drawing, the numeral 1 designates a belt, sling or other means of attachment to the body to be lowered. A wire cable 2 or other 40 flexible connection from the sling, passes over a drum 3 rotatable on a shaft 4 journaled in bearings carried by pedestal brackets 5—5' forming part of, or fastened in, a strong casing 25 which is firmly secured by bolts or otherwise to the wall 45 above a window or other place where it may be used.

The ends of said shaft are provided with double-crank 6—6' extending diametrically opposite to the shaft, and the wrist pins 7—7' thereon are operatively connected by links 8—8' to retarding means comprising for example pistons mounted in vertical cylinders 9—9' securely fastened adjacent to said pedestal brackets and in the rotary plane of the wrist pins. A pipe 10 connects the bottom of said cylinders, and a valve 50

casing 11 is interposed midway thereof. In this casing is horizontally mounted a tapering barrel 12, having transverse holes 13 of different diameters which successively match opposing ports 14—14' in said casing and form respective through passages when the barrel is rotated by a crankarm 15 which points to a series of numbers representing pounds circumferentially spaced on a dial disk 16 indicating approximately the weights to be lowered, and corresponding inversely to the holes in said barrel,—that is, the smaller holes correspond to the larger weights to be lowered.

The said pistons are preferably single acting, and the spaces below them and also the connecting pipe with its regulating valve, are filled with a constant liquid, non-freezing and non-evaporating, such as used in auto hydraulic brakes.

The weight of a body suspended in said sling 20 pulls on the wire connection and rotates the drum shaft, causing the cranks to operate the pistons alternately up and down in their respective cylinders, and thus force the contained liquid to shift from one cylinder to the other alternately, at a speed regulated by the size of the hole in 25 the barrel that is in adjusted communication with the ports of the casing.

For instance, the indicator crank arm when set for 150# weight, provides a smaller hole and hence a greater resistance to liquid passage 30 therethrough, than when said arm is set for a 50# weight for which a correspondingly larger hole in the valve provides lesser resistance for the flow of liquid back and forth between the cylinders. The greater the weight of the body 35 being lowered the greater is the rotative pull on the drum, and the greater is the required resistance to the flow of liquid between the cylinders obtained by the successively smaller holes corresponding inversely to the weight numbers on 40 the dial disk to which the indicator crank arm is set. The indicator arm is set to a number on the disk which is somewhat less than the weight of the body to be lowered, according to the desired speed of its gravitating descent. The difference between the indicated weight number and the actual weight of the body to be lowered, 45 should be sufficient to overcome the friction of operating the device and allow a safe rate of descent of the suspended body.

The device can also be used for lowering boxes or bundles from an upper floor automatically.

For quickly rewinding the flexible connection on the drum, the drum is provided with a spring-controlled ratchet clutch connection to the crank 55

shaft, by which the drum can be turned backward without turning the crank shaft. For example, one hub of the drum has ratchet teeth 20 engaging matching teeth 21 on a collar 22 fixed to the shaft, and held in such engagement by a coil spring 23 pressing against the opposite hub of the drum, making a positive clutching engagement when a body or other weight is being lowered as above described. In rewinding the flexible connection, the drum is rotated backward by hand, and slides axially on the crank shaft compressing the coil spring to disengage the teeth and allow the drum to turn backward without operating the crank shaft and its connections. The flanged rims 24 of the drum facilitate such manual rotation.

I do not confine myself to the construction shown for carrying out my invention except by the appended claims.

20 I claim:

1. A lowering device having, in combination a shaft, a drum mounted thereon, a flexible member wound on said drum for lowering a descending weight, retarding means operatively connected to said shaft and including chambers containing liquid under pressure induced by said descending weight and connected by a pipe subject to flow of liquid, and regulating means for said liquid characterized by a valve casing having ports communicating with said pipe, and a barrel rotatably adjustable in said casing and having transverse holes of different diameter successively matching said ports, substantially as described.

35 2. A lowering device having, in combination a drum, a flexible member wound thereon for lowering a descending weight when unwinding said member, and retarding means including chambers containing liquid under pressure induced by said descending weight and connected by a pipe subject to a flow of liquid, and regulating means characterized by a valve casing interposed in said pipe having ports connected to said pipe, and a barrel rotatably adjustable in said casing and 40 having transverse holes of different diameter successively matching said ports, and a crank arm on said barrel for adjusting different holes

of said barrel to vary the flow, substantially as described.

3. A lowering device having, in combination a drum, a flexible member wound thereon for lowering a descending weight supported thereby, retarding means controlling the rotation of said drum and including chambers containing liquid under pressure of said descending weight and connected by a pipe subject to flow of liquid between said chambers, a regulating valve casing in the course of said pipe, a rotatably adjustable barrel mounted in said casing, having various sizes of holes, an indicator crank arm on said barrel, and a disc adjacent to said arm bearing numbers spaced circumferentially in a series indicating weights and inversely corresponding to said holes in said barrel, substantially as described.

4. A lowering device having, in combination a double crankshaft, a drum slidable axially and rotatably thereon and having ratchet teeth on one end hub, a flexible member wound on said drum for rotating the drum under pull of a descending weight, retarding means operatively connected to said shaft, a collar fixed on said shaft and having ratchet teeth normally engaging said hub teeth, and a coil spring on said shaft pressing the hub teeth into positive engagement with the collar teeth to transmit the retarding action to the drum while the flexible member is unwinding, and allow the drum to turn freely on the shaft when the drum is rotated backward to wind thereon said flexible member, substantially as described.

5. A lowering device comprising a crankshaft, a drum rotatable on said crankshaft, a flexible member wound on said drum, a ratchet clutch between said drum and shaft, a spring mounted on the shaft acting on the clutch to connect and rotate said drum and shaft in unison under pull of a descending weight attached to said flexible member and allow disengagement of said drum in reverse rotation of the drum, and retarding means operatively connected to the crank of said shaft to retard unwinding of the flexible member, substantially as described.

EDGAR SCHOENE.
